EMERGENCY SLUICE

Karl Schön, Wurzburg, Germany

Application November 18, 1933, Serial No. 698,673
In Germany November 21, 1932

10 Claims. (Cl. 61—29)

My invention relates in its broad aspects to improvements in the erection, maintenance and repair of water retaining structures in general, including weirs, dams, overfalls, locks, sluices and like structures of various description, collectively called hereinafter "barrages", built as obstructions into the bed of a river or other stream of water for the purpose of stowing up and raising the water to a higher level—for instance for forming a stretch of navigable deep water or a huge natural water reservoir, for diverting the water to a canal leading to a hydraulic power station, to irrigation ditches or the like.

The invention relates more especially to the problem of speedily placing an emergency sluice gate for temporary use only in front of the barrage under consideration at the upstream side of the latter, viz. so as to provide at the back of the emergency sluice a substantially dry space or trench free from water, from which all those parts of the barrage which are generally submerged in the water, such as dewatering appliances, sluice-gates, joints, supports, hinges, gears, culverts, sills, spillways etc. are readily accessible for inspection, overhauling and repair.

The object of the invention, its salient features, and the advantages obtained thereby will be better understood by reverting first to one of the latest types of emergency sluices known in the art, which is diagrammatically illustrated in Fig. 10 of the accompanying drawings:

The emergency sluice shown in Fig. 10 comprises a series of rollers A, spanning the floodway B and being fitted in horizontal position within a frame C so as to have a free rolling motion upon the front faces D' of the dam D, with which the rollers A are kept in contact by the energy of the flowing water.

Frame C is suitably braced by diagonal bars (not shown) and surmounted by a crosshead E, to which the lifting hook of a hoisting machine—e. g. a crane, travelling on the top of dam D, are attached.

The said rollers A and the frame C constitute a self contained unit which can be lifted and lowered as a whole.

It is evident that at all events considerable head room must be available above the site of the emergency sluice described, and that a crane or other rather costly or cumbersome appliance such as a derrick or other hoisting machine, working on a dam, a bridge, a floating platform, barge etc., is required together with a trained staff or workmen for handling the heavy emergency sluice gate structure concerned on placing it into its

operative position and removing it therefrom ultimately.

The principal object of this invention is to overcome these drawbacks by providing an emergency sluice of improved yet simple design which is composed of a plurality of individual gate units of relatively light weight, easy to be handled and capable of being put into their operative position and removed therefrom by hand, and without the aid of a crane, a dam, a bridge, a floating derrick, or like contrivances.

The invention further aims at so designing the emergency sluice gate and the bank work of the river cooperating therewith that tight joints are obtained at all parts, packing faces etc. of the gate structure which are in contact with each other and with the bank work of the river, so as to effectively eliminate leakages and to safely hold back the stowed up water from the trench interposed between the emergency sluice, and the barrage concerned.

Another object of the invention is to provide an improved emergency sluice, the gate units of which and the bank work of the river cooperating therewith are so designed, that the energy of the flowing water passing down stream through the cross sectional area of the river, where the sluice gate is to be set up, is utilized for automatically starting the gate units concerned on being ready for descending into their operative position.

Other objects of the invention will become incidentally apparent hereinafter to practitioners in this field.

The nature and scope of the invention are briefly outlined in the appended claims and will be more fully understood from the following specification taken together with the accompanying drawings in which an embodiment of the invention is shown by way of an example.

Fig. 1 is a lay-out, showing in cross section all the units, of which the improved emergency sluice gate is composed, floating on the river and being at this initial stage of the setting up operations in readiness to be placed into engagement with specially shaped reinforcements or linings of the bank work, described hereinafter with reference to Fig. 5.

Figs. 2 and 3 diagrammatically show in which manner a torque, resulting from the stowed up flowing water, will act upon each unit of the sluice gate on having been brought into engagement with tooth racks provided at the front faces of the bank work of the river.

Fig. 4 shows in cross section the whole emer-

gency sluice gate with all its units in their final operative position,

Fig. 5 is a plan, partly in section, showing in a larger scale the principal structural features of 5 one of the sluice gate units and those of the bank work of the river the direction of flow being indicated by arrows,

Fig. 6 is a fragmentary cross section, taken vertically through one of the sluice gate units, 10 showing the latter in operative position, immersed in the river, in an equally large scale,

Fig. 7 is a section taken vertically through one of the tubes, used as auxiliary packing members, viz. for closing up gaps intermediate the sluices 15 gate proper and the bank work of the river,

Figs. 8 and 9 are cross sections through sluice gate units of modified design.

Fig. 10 illustrates in cross-section a type of 20 emergency sluice known in the art.

Principles of construction and operation

According to this invention the sluice gate structure is composed of a plurality of separate 25 damming units, for instance five in number designated I, II, III, IV, V, which are floatingly brought to the place where the emergency sluice is to be set up, viz. floating in a cross wise position relatively to the direction of flow, as seen in Fig. 1.

The said damming units are adapted to be assembled on top of each other in the river bed, as 30 seen in Fig. 4: For the reception of and engagement with the damming units the banks of the river to be dammed up are reinforced at B, B' for instance by masonry, ferro concrete linings, etc., and are specially shaped, as seen in Figs. 4 and 5, so as to present a gate way; the latter is enclosed by shoulders S, S', crosswise projecting into the river bed and presenting at their head water side 35 vertically disposed abutments or faces 10, 10', and by a sill S'' at the bottom of the river, presenting a substantially horizontal and even surface 10'' intermediate the said shoulders in front thereof (Fig. 4).

With the embodiment of the invention shown 40 in Figs. 1, 4-6 the units I-V are made in the form of tubes or drums of preferably circular cross sectional shape, hereinafter called "damming drums". The latter are closed at both ends and 45 are so designed and equipped with guiding, locking and packing means that, on having been brought into cooperative engagement with corresponding guiding, locking and packing means provided at the bank work of the river, and on 50 having been filled thereupon with a proper weight of water (Fig. 4), each damming drum will sink and rotatably descend automatically into its operative position at the gate way of the river, each 55 one singly after its predecessor.

Another salient functional feature inherent to 60 the damming drums, of which the emergency sluice gate structure is composed, is diagrammatically shown in Figs. 2 and 3:—

By each damming drum, which floatingly comes 65 into contact with the abutments 10, 10', the water of the river is stowed up to a height $h' + h''$, and produces a torque $P \cdot H$ upon the drum, viz. in anticlockwise direction inasmuch as the resulting force of the mechanical impact and the hydrostatic pressure, graphically determined and indicated by arrow P in Figs. 2 and 3, acts at a height

$$H = \frac{1}{3}(h' + h'')$$

viz. below the actual point of contact and support

i, from which the drum I will travel in the direction of arrow x.

Salient accessorial structural features:

(a) Guiding and locking means

As seen in Figs. 5 and 6 tooth racks 12, 12', rails 14, 14' and reinforced notches 16, 16' are provided at the shoulders S, S' and at the bank work B, B' of the river for safely guiding and retaining the 10 damming drums during and after their travel into their operative position—and when ultimately the sluice gate structure is taken apart.

For cooperation with the said guiding and locking means gear wheel rims 2, 2', guide rails 4, 4' and resiliently mounted pins 6, 6' are provided at 15 both ends of the damming drums.

Self-engagement of the said resilient pins 6, 6' with the notches 16, 16' is conveniently afforded by forming the bank work of the river with rounded off corners F, F' (Fig. 5); thus the drum under treatment on drifting down the river and approaching the site of the emergency sluice in proper position, viz. floating crosswisely on the river, will automatically come into locking engagement with the tooth racks 12, 12' and the locking notches 16, 16'; the latter are wide enough to allow of temporarily disengaging the drum from the tooth racks for adjusting it by hand and with the aid of marks (not shown) in its individual initial angular position, determined with regard to the point i of engagement with the tooth racks 12, 12' and the individual length of travel, measured circumferentially, until reaching its final operative position.

(b) Loading the damming drums with water ballast and discharging the latter

In order to enable the hollow drums I-V to 40 safely withstand the different hydrostatic pressures to which each drum is individually subjected and to provide drums of the smallest possible net weight, consistent with the appropriate mechanical strength and rigidity, the drums are given walls of different thickness, as best seen from the hatched lines in Figs. 1 and 4, graduated in proportion to the respective hydrostatic pressure; drum I having the thickest walls, while drum V has the thinnest ones.

Means are provided for loading the drums with 45 water ballast, as required first (Fig. 1) on floatingly placing them into engagement with the tooth racks 12, 12' and secondly (Fig. 4) for their descent:

With the embodiment of the invention, shown 50 by way of an example in the drawings, the said loading means comprise water admission valves 21-24, resiliently mounted at a partition wall 30, which crosswisely extends through the drum and subdivides it into two chambers of widely 55 different size, a small one 40 and a large one 50.

Two sets of valve actuating mechanism are provided for opening and closing the inlet valves 21-24, the primary one comprising a screw and nut gear 25, a yoke 26, which cooperatively interconnects said gear and valves, and a hand wheel 27 attached to gear 25. Hand wheel 27 is accessible for being revolved by hand through a plurality of slots or apertures 41, provided in the circumferential walls of chamber 40.

On opening the inlet valves river water will enter through the apertures 41 into chamber 50, filling the latter, while the drum descends, up to the level shown in Fig. 4. The total volume of water ballast entering depends on the radial 70

distance of the valves 21—24 and the volume of air incidentally retained in the drum.

The secondary valve actuating mechanism is arranged in the large chamber 50 of the drums 5 and is operable from the rear side of the latter, viz. from the trench intermediary the emergency sluice gate and the barrage under construction or repair; said secondary valve actuating mechanism comprises a pair of bevel gear wheels 28 10 keyed to screw spindle 25, a shaft 29 for operating said bevel gear wheels and extending outwardly through the circumferential wall of the drum, and a hand wheel 29a, detachably fixed on shaft 29.

15 On closing the inlet valves 21—24 by means of the secondary actuating mechanism and opening the discharge valves 51—55, which are also accessible from the rear side of the drums (Fig. 4) the greater portion of the ballast water will flow out; as seen in Fig. 4 the discharge valves 51—55 20 are attached to the individual drums at different heights relatively to their upper and lower packing ledges 71—75, viz. so that, on opening said valves, predetermined quantities of ballast water 25 will remain in the drums:—viz. the places of the discharge valves being so chosen, that the ballast-water retained in each drum compensates the differences in net weight resulting from the graduated thickness of their walls referred 30 to above, and will cause the drums to float at an appropriate—preferably equal—depth of immersion, as seen in Fig. 1.

For counterbalancing the one-sided load represented by the partition wall 30 and members 35 attached thereto, inlet valves 21—24 and both their actuating mechanisms, a counter-weight 56 is provided in chamber 50, so arranged and chosen as to ensure equilibrium and cause the drums to float in substantially horizontal position.

(c) *Packing means for securing tight joints*

As seen in Figs. 4 and 6 packing ledges 71—75, 45 preferably made of elastic material such as india-rubber, cork, wood, compressed fibers, etc., and presenting smooth surfaces, are fixed longitudinally on the damming drums in diametrical position to each other; the radial thickness of said ledges being so chosen, that the latter will be 50 in intimate and firm contact with each other and the sill face 10" and thus provide water tight joints, when the drums reach their operative position.

In addition to said packing ledges shields or plates 81—85, suitably braced by ribs or the like, are fixed on the damming drums I—V near both ends, so as to outwardly project therefrom, and form—together with bevelled edges 86, 86' of the base plates of the tooth racks, 12, 12'—wedge shaped gaps:

Packing rods or poles 80, 80', preferably of tubular shape and being provided at their lower ends with an orifice 8a for the draining off water and with a plug 8b of resilient material, 65 are to be inserted into said wedge shaped gaps, whereby water tight joints are obtained.

It should be noted and will be best seen from Fig. 6, that the packing plates 81—85, in order to tightly interfit with their upper and lower edges, must be formed with projections and recesses of epicycloidic shape 8c, 8c', in as much as the corner point c of each packing plate lies below the pitch line of the tooth rack 12, and runs in an epicycloidic curve, indicated by a dot-

ted line e, while the drum rotatably descends into its operative position.

For removing the emergency sluice gate described above the ballast water must be first drained off the drums by closing their inlet valves 5 21—24 and opening the discharge valves 51—55; whereupon the trench at the rear of the emergency sluice gate is filled with water, admitted for instance through a by-pass canal.

On withdrawing the packing poles 80, 80' the 10 drums, because of their restored buoyancy, are free to rise to the surface of the river and will float thereon ready for being removed and saved for future use.

Various changes and modifications may be 15 made in the structural details of emergency sluices of the improved design, described above, and in the shape and cooperation of the component parts, without departing from the spirit and the salient ideas of this invention. For instance the damming drums may be given in special cases an elliptical or polygonal cross sectional shape—instead of a circular one—as indicated in Figs. 8 and 9.

I am aware that it has been attempted, to 20 build up emergency sluice gates from hollow caissons, which are filled with ballast water like a floating dock, which in sinking are to be assembled on top of each other, and from which the ballast water must be removed by pumps, 30 so as to restore their buoyancy; and I make no claim whatever on emergency sluice gates made of caissons of that nature.

Instead of a plurality of damming drums a 35 single one may suffice in extraordinary cases.

What I claim is:

1. In an emergency sluice, the combination with a water gate structure of a plurality of superposed damming drums adapted to float on the water and in turn to be submersed therein 40 so as to be assembled on top of each other for cooperative interengagement with each other and the water gate structure, submerging appliances on said drums, guiding means on opposite ends of said drums, and means on the gate structure 45 adapted to receive said guiding means, whereby the drums rotatably descend into their operative position on being submersed.

2. In an emergency sluice, the combination with a water gate structure of a plurality of superposed damming drums adapted to float on the water and in turn to be submersed therein 50 so as to be assembled on top of each other for cooperative interengagement with each other and the water gate structure, submerging appliances on said drums, including means for admitting ballast water into the drums and means for discharging ballast water therefrom, guiding means on opposite ends of said drums, and means on 55 the gate structure adapted to receive said guiding means, whereby the drums rotatably descend into their operative position on being submersed.

3. In an emergency sluice the combination with a water gate structure of a plurality of superposed damming drums adapted to float on the water and in turn to be submersed therein 60 so as to be assembled on top of each other for cooperative inter-engagement with each other and the water gate structure, submerging appliances on said drums including means for admitting ballast water into the drums and means for discharging ballast water therefrom; said ballast water admitting means comprising 65 a partition wall subdividing each drum into two chambers of widely different size, a plurality of 70

chambers of widely different size, a plurality of 75

- valves mounted on said partition wall provided with two sets of valve actuating mechanism, the primary one being located in the smaller chamber accessible through apertures in the circumferential walls of said chamber and the secondary one being located in the larger chamber and provided with actuating means extending through the circumferential walls of said larger chamber, guiding means on opposite ends of the drums, and means on the gate structure adapted to receive the said guiding means, whereby the drums rotatably descend into their operative position on being submersed.
4. In an emergency sluice, the combination with a water gate structure of a plurality of superposed damming drums adapted to float on the water and in turn to be submersed therein so as to be assembled on top of each other for cooperative inter-engagement with each other and the water gate structure, submersing appliances on said drums, packing means on each drum for producing substantially water tight joints where the drums are in engagement with each other and the gate structure, guiding means on opposite ends of the drums, and means on the gate structure adapted to receive the said guiding means, whereby the drums rotatably descend into their operative position on being submersed.
5. In an emergency sluice, the combination with a water gate structure of a plurality of superposed damming drums adapted to float on the water and in turn to be submersed therein so as to be assembled on top of each other for cooperative inter-engagement with each other and the water gate structure, submersing appliances on said drums including means for admitting ballast water into the drums and means for discharging ballast water therefrom, said ballast water admitting means comprising a partition wall subdividing each drum into two chambers of widely different size, a plurality of valves mounted on said partition wall provided with two sets of valve actuating mechanism, the primary one, located in the smaller chamber and operable through apertures in the circumferential walls of said chamber, comprising a screw and nut gear, a yoke cooperatively interconnecting said gear with the valves, and a hand wheel attached to said screw, the secondary valve actuating mechanism, located in the larger chamber and operable from without said chamber comprising a shaft extending through said partition wall and attached to said screw and nut gear, a bevel gear adjacent the other end of said shaft, and a second bevel gear, which cooperates with said first bevel gear and is mounted on a shaft extending through the circumferential walls of said larger chamber, guiding means on opposite ends of the drums, and means on the gate structure adapted to receive the said guiding means, whereby the drums rotatably descend into their operative position on being submersed.
6. In an emergency sluice, the combination with a water gate structure of a plurality of superposed damming drums adapted to float on the water and in turn to be submersed therein so as to be assembled on top of each other for cooperative inter-engagement with each other and the water gate structure, submersing appliances on said drums including means for admitting ballast water into the drums and means for discharging ballast water therefrom, said ballast water admitting means comprising a partition wall subdividing each drum into two chambers of widely different size, a plurality of valves mounted on said partition wall, provided with two sets of valve actuating mechanism, the primary one being located in the smaller chamber accessible through apertures in the circumferential walls of said chamber, and the secondary one being located in the larger chamber and provided with actuating means extending through the circumferential walls of said larger chamber, the said larger chamber being provided at one end with a weight to counter-balance the weight of the partition wall at the other end so as to cause the damming drum to float in a substantially horizontal position, guiding means on opposite ends of the drums and means on the gate struc-

ture adapted to receive the said guiding means, whereby the drums rotatably descend into their operative position on being submersed.

6. In an emergency sluice, the combination with a water gate structure of a plurality of superposed damming drums adapted to float on the water and in turn to be submersed therein, so as to be assembled on top of each other for cooperative inter-engagement with each other and the water gate structure, submersing appliances on said drums, packing means on each drum for producing substantially water tight joints where the drums are in engagement with each other and the gate structure, guiding means on opposite ends of the drums, and means on the gate structure adapted to receive the said guiding means, whereby the drums rotatably descend into their operative position on being submersed.

7. In an emergency sluice, the combination with a water gate structure of a plurality of superposed damming drums, adapted to float on the water and in turn to be submersed therein so as to be assembled on top of each other for cooperative inter-engagement with each other and the water gate structure, submersing appliances on said drums, packing ledges extending longitudinally along the top and bottom respectively of each drum, packing plates projecting outwardly adjacent the ends of each drum, packing poles, interposed between said packing plates and gate structure, guiding means on opposite ends of the drums, and means on the gate structure adapted to receive the said guiding means, whereby the drums rotatably descend into their operative position on being submersed.

8. In an emergency sluice, the combination with a water gate structure of a plurality of superposed damming drums, adapted to float on the water and in turn to be submersed therein so as to be assembled on top of each other for cooperative inter-engagement with each other and the water gate structure, submersing appliances on said drum, packing ledges extending longitudinally along the top and bottom respectively of each drum, packing plates projecting outwardly adjacent the ends of each drum, a tubular packing pole having a resilient plug in its lower end and provided with a hole above said plug for admission and discharge of water, interposed between the packing plates on each end of the drums and the adjacent gate structure, guiding means on opposite ends of the drums and means on the gate structure adapted to receive the said guiding means, whereby the drums rotatably descend into their operative position on being submersed.

9. In an emergency sluice, the combination with a water gate structure of a plurality of superposed damming drums adapted to float on the water and in turn to be submersed therein so as to be assembled on top of each other for cooperative inter-engagement with each other and the water gate structure, submersing appliances on said drums, resiliently mounted pins on opposite ends of said drums, vertical reinforced notches in the bank work of the gate structure, said notches being arranged directly opposite each other and adapted to receive the said resiliently mounted pins, whereby the drums rotatably descend into their operative position on being submersed.

10. In an emergency sluice, the combination with a water gate structure of a plurality of superposed damming drums adapted to float on the water and in turn to be submersed therein, so as to be assembled on top of each other for co-

operative inter-engagement with each other and the water gate structure, submersing means on said drums, a gear wheel rim adjacent each end of the drums, resiliently, axially mounted pins on 5 opposite ends of the said drums, vertical reinforced notches in the bank work of the gate structure, said notches being arranged directly opposite each other and adapted to receive the

said pins, shoulders projecting crosswisely from said gate structure presenting substantially vertically disposed abutments facing head water, and tooth racks on said abutments adapted to cooperate with the said gear wheel rims whereby the drums rotatively descend into their operative position on being submersed. 5

KARL SCHÖN.
